United States Patent Office

Des. 219,096
Patented Nov. 3, 1970

219,096

BOTTLE

Francisco Mauri-Closa, Barcelona, Spain, assignor to Sopec, S.A., Barcelona, Spain

Filed Mar. 12, 1969, Ser. No. 16,194

Term of patent 14 years

Int. Cl. D9—01

U.S. Cl. D9—2

FIG. 1

FIG. 3

FIG. 1 is an elevational view of a bottle showing my new design;

FIG. 2 is another elevational view looking from the right of FIG. 1, the side opposite that shown being the same in appearance; and

FIG. 3 is a top plan view thereof.

The bottom is plain and ornamented.

I claim:

The ornamental design for a bottle, as shown and described.
